DESIGN FOR A TOY

James Bunnell, Denver, Colo.

Application March 6, 1945, Serial No. 118,291

Term of patent 7 years

(Cl. D34—15)

To all whom it may concern:

Be it known that I, James Bunnell, a citizen of the United States of America, residing at Denver, in the county of Denver and State of Colorado, have invented a new, original, and ornamental Design for a Toy, of which the following is a specification, reference being had to the accompanying drawing, forming part thereof.

In the drawing:

Fig. 1 is a side view of a toy showing my new design; and

Fig. 2 is an edge view thereof.

The interlining on the drawing designates color. The opposite side of the toy is ornamented similarly to the side illustrated in Fig. 1.

I claim:

The ornamental design for a toy, as shown and described.

JAMES BUNNELL.
